[52] U.S. Cl. 139/12

Apparatus for controlling the movement of shaft rods in progressive shed looms, that is, weaving looms which perform the simultaneous weaving of weft threads, the shaft rods performing a wave-like harmoniously repeated continuous shedding movement by individual sections. Counter-movement of at least two shaft rods of one section moving in forced opposite directions is provided by one lever means which is phase shifted with respect to the other sections and reciprocates in accordance with the phase shift. The ratio of arms of the lever means is changeable, the point of tipping of the lever means being adjustable. To close the sheds, the symmetrically dead center area of the lifting means of the shaft rods is symmetrically limited, and thereafter the said shaft rods are displaced into alignment.

FIG. 10

CONTROL APPARATUS FOR WAVE SHED FORMING MEANS

The present invention relates to an apparatus for controlling the movement of shaft rods in looms with simultaneous weaving of weft threads, wherein the shaft rods perform a wave-like harmoniously repeated continuous shedding movement in which half the number of shaft rods in each section determine or form the upper part of the shed and the second half of the shaft rods determine or form the alternating lower part of the shed.

Various devices for the formation of a wave-like harmoniously repeated shedding movement have been suggested wherein the individual rods with their consecutively arranged shafts have been grouped into sections. The rods, however, in consequence of the space required for the separately disposed driving means, could not be arranged in a row, but have been laterally offset with respect to one another.

Consequently, in such known devices independent drive means for lifting and lowering every rod are indispensable, said drive means comprising, e.g. eccentric rotary pins arranged on a common drive shaft traversing the entire width of the wave weaving loom and, usually, double-arm levers insuring the transmission of the rotary movement of the said eccentric pins angularly shifted with respect to one another, and possibly angularly shifted cams for the respective shaft rods.

Another known apparatus for creating a travelling-wave harmoniously repeated shedding movement, employs heddles forming the angle of the shed at the end of which the fabric closes, during the deflection of these heddles a shuttle with weft travelling through the shed. The heddles are threaded at least on one wire which is freely flexible and which is gripped at certain intervals by lifting hooks moving forcedly up and down with a phase shift, inducing the wave-like motion of said wire. The reciprocating movement of the lifting hooks is actuated by means of helically threaded control shafts traversing across the looms.

Further known devices for the formation of a travelling-wave shed in looms with simultaneous weaving of weft threads consist, among other embodiments, of rotating cams arranged on a cam drum on a common drive shaft passing across the loom, wherein each cam is offset with respect to the adjacent one in a certain phase-shift, and during its rotation affects a certain number of threads in the warp system, thus imparting directly to them the necessary shedding stroke in the series of strokes determined by the arrangement of the cams.

Among these devices there can also be mentioned a system of electromagnetic selecting means for lifting the heddles, wherein the said heddles are hung from a flexible wire on which small weights are fixed at appropriate intervals, said weights operating at the same time as armatures of electromagnets.

Each of these known devices for creating a wave-like harmoniously repeated continuous shedding movement in which the shaft rods, the heddles, and possibly also the warp threads and the like participate, solves in a way the problems of a progressing shed. However, each of them has some specific drawbacks, such as a very high degree of warp thread wear, excessive complexity of production of the machinery, difficult maintenance, and in most cases limited working speed.

It should be stressed quite particularly that the previous known devices have been predominantly oriented to the design and the improvement of means capable of producing a continuous wave-like shedding movement, without, however, taking into consideration, to a sufficient extent, some very important requirements on the side of weaving technology, particularly from the viewpoint of the preparation and of the weaving process itself.

10 The known devices substantially lack the possibility, while some of them preclude it altogether because of their fundamental design factors, of regulating the value of the amplitudes of all wave sheds, to adjust the heights of individual shafts, further to close all shed waves, thus aligning all warp threads in one plane, and last but not least, the possibility of drawing in the warp threads outside the loom, or of exchanging the heddles outside the loom.

20 The present invention avoids all of the above-mentioned disadvantages of known devices and methods, while pursuing the aim of creating a simple method of controlling the movement of shaft rods, and while taking fully into consideration the highly important requirements of weaving technology, so that, for example:

a. the optimum weaving conditions can be adjusted, especially when weaving from different material, by changing the amplitude (height) of the shed wave;

30 b. all shed waves can be removed, i.e. all warp fell of the just woven can be aligned into one place to enable the warp threads to be machine joined;

c. the undesirable sliding of heddle eyes on warp threads is avoided or at least reduced to a considerable degree by arranging the motion of heddle eyes along a circular path the imaginary center of which lies in the weaving plane in the area of prewoven fabric;

35 d. a part or the entire shedding mechanism can be removed, enabling the warp threads to be more easily drawn in into the eyes of the heddles; this can have a considerable beneficial effect upon the productivity of the weaving loom;

e. the arrangement of secured eccentric pins in the 45 rotary connections of the shedding mechanism permits very precise adjusting of every rod, and consequently also every shaft with respect to one another, in order that the side dead centers of all shafts be identical across the entire width of the warp with respect to the weaving plane;

f. the division of the shedding mechanism into single 50 units facilitates the assembly of the loom, production thereon, and later on also the maintenance of the loom;

55 g. the presence of one driving cam or one eccentric member in a section serve, in cooperation with a suitable lever means, to actuate all working movements of the shaft rods, and possibly also the movements of the heddles.

In accordance with the invention, the counter-movement of at least two shaft rods of one section moving in forced opposite directions is actuated by a lever means which is phase shifted with respect to the other sections and reciprocates in accordance with the phase shift; the ratio of arms of the lever means is changeable and the point of tipping being adjustable; after excluding the cams, while symmetrically limiting the dead center area of the lifting means of shaft rods, the said shaft rods are displaced into alignment.

Further advantages and features of the invention will be more fully explained in the following detailed description read with the accompanying drawings in which:

FIG. 1 is a side view of the general embodiment of one section of a first embodiment of the extractable shedding mechanism with a horizontal drive, a control system and mechanism for closing the shed waves;

FIG. 2 is a side view of the general embodiment of an alternative extractable shedding mechanism with a vertical drive and a mechanism for closing the shed waves;

FIG. 3 is a view in plan of an alternative embodiment of the shedding mechanism according to FIG. 2, the drive mechanism being omitted for clarity of illustration;

FIG. 4 schematically illustrates the lifting means of the shaft rods and shows the paths of the heddle eyes;

FIG. 5 is a view of the cam and its adjacent link of the drive mechanism of one section;

FIG. 6 is a view in cross-section of a cam and a link of the drive mechanism, the section being taken along line 6-6 of FIG. 5;

FIG. 7 is a detailed illustration of a rotatable and shiftable connection of the control system and the lifting means of the shaft rods using a secured eccentric pin;

FIG. 8 is a view in axial section of the rotatable and shiftable connection according to FIG. 7, the section being taken along the line 8-8 of FIG. 7;

FIG. 9 is a diagrammatic representation of the device for closing the shed waves in one section;

FIG. 10 is a fragmentary view in front perspective of a loom incorporating the shedding mechanism shown in FIGS. 1 and 2 of the drawings.

The following description relates to one section of the shedding mechanism only, the plurality of other sections in the loom being identical.

As shown in FIG. 1, the shedding device according to the present invention consists of four main units cooperating with each other: a drive mechanism 1, a lifting means 2, a control system 3, and a device for eliminating the shed waves and bringing all of the warp threads into a single plane. The shedding device has main frames 5.

In a basic embodiment of the extractable or removable shedding mechanism 1 with a so-called horizontal drive (see FIG. 1) the drive mechanism 1 is formed substantially by a drive shaft 11 which crosses the loom and by cams 12 (one shown) with which the shaft is provided. The cams 12 are angularly displaced with respect to each other with a certain phase shift, and their number corresponds with that of the individual sections of the shedding mechanism, which is further determined by the weaving width of the loom and by the number of cycles of the shed wave.

Each of the cams 12 is provided at both sides with a shouldered hub 121 (FIG. 5) which is continuously contacted with the guiding surface 13a of spaced parallel glide members 13, 13' of a horizontally arranged link 15. At the side with which it is adjacent to cam 12 the link 15 has the shape of a double fork with an inserted roller 14. The ends of the bifurcated lever 15, arranged one above the other, carry cross bars 16 which are adjustable around a pin 17, each bar 16 being provided with a slot 18 through which a fixing bolt 19 extends. A second roller 14' is disposed between each pair of these cross bars 16.

The rollers 14, 14' of the link 15 roll around the cam 12, the shape of which insures a constant distance of the centers of rollers 14, 14' during their continuous rolling around the cam 12, while the connecting line 123 of said centers always intersects the axis of rotation 122 of cam 12.

As shown in FIG. 1, the link 15 is pivotally connected by means of a pin 210 to a lever 21 which forms part of the lifting means 2. The lever 21 has at one end a head 211 (at the top in FIG. 1) and a fork 212 at the other end. The lever 21 is connected to the direct lever lifting means 2 for the rods 25 and 27 of shafts (not illustrated) by means of said head 211. These direct lever lifting means 2 comprise at least one three-arm lever 22 and one double-arm lever 24.

The three-arm lever 22 of the lifting means 2 is rotatably connected with the head 211 of the lever 21 and is pivotally mounted on a lower pin 221' of the holder 222 of the section. The second, intermediate arm of the three-arm lever 22 is pivotally connected to the lower end of the rear rod 27 of the shaft; an upper guide arm 28 which is rotatably mounted on the upper pin 221 of the holder 222 of the section is pivotally connected to rod 27. The upper pin 221 also serves as the fulcrum of the adjacent double-arm lever 24. One arm of the double-arm lever 24 is pivotally connected to the front rod 25 of the shaft, rod 25 being pivotally connected at its lower end to a lower guiding arm 26, which is rotatably mounted close to the three-arm lever 22 on the common lower pin 221' of the holder 222 of the section. The second arm of the double-arm lever 24 is pivotally cross-connected by means of a connecting rod 23 back to the third arm of the three-arm lever 22. This entire unit, which consists of a holder 222 with a three-arm lever 22 and a lower guide arm 26 rotatable on the lower pin 221, and the upper guide arm 28 with the double-arm lever 24 on the upper pin 221, and the front and rear rods 25 and 27 of the shafts, is independently extractable from the frame of the loom.

The control system 3 is carried by the cross beam 53. System 3 has its vertical position determined by set screws 301 and is secured in adjusted position by bolts 302. Two or more brackets 30 arranged to form a rigid

unit on the cross beam 53 carry two shafts 31 and 41 parallel with the cam shaft 11. Shaft 31, which is fixed, is provided with a set of bell cranks 32 which can be turned individually; the number of cranks 32 is the same as the number of lifting means 2. As shown in FIGS. 7 and 8, the generally vertical arm of bell crank 32 carries an eccentric pin 34 with a fixing bolt 35. On the eccentric pin 34 a slide 33 is loosely journaled so that it can be shifted to project into the fork 212 of the lever 21, serving as its tipping point.

At the outer end of the other arm of the bell crank 32 a disc 321 is rotatably mounted, disc 321 being gripped by the open edge of the surfaces 421, 420 (FIG. 9) of the functional part of a segment 42, which is arranged on a rotatable shaft 41.

By adjusting the eccentric pin 34 the slide 33 is shifted in the fork 212 on the lever 21, thus changing the position of slide 33 with respect to the axis V (FIG. 1), and, consequently, also the mutual vertical position of the rods 25 and 27. By the vertical shifting of the brackets 30 on the cross bar 53 the transmission ratio of the arms of all levers 21 change to a rather considerable extent.

On the rotatable shaft 41 there is disposed a row of segments 42 the number of which is the same as that of the discs 321, that is, the number of the sections. All of said segments are simultaneously controlled by turning the shaft 41 by means of a sprocket 43 (FIG. 9). The chain 44 which is entrained over the said sprocket 43 passes into engagement with the sprocket 45 of the profile bar 452, then passes in a reverse direction about sprocket 46 of profile bar 462, and thence to coil tension spring 47, as shown.

The profile bars 452 and 462 of the device 4 for closing the shed waves are fixedly secured to the respective rotatable shafts 451, 461. Said bars are disposed across the loom in the area of the dead centers of individual heads 211 of the levers 21, that is to say, in the area of the dead centers of the lifting means 2, e.g. the three-arm levers 22.

The described shedding device is arranged between sidewall members 51 which are connected to each other by cross beams 52, 53. The shedding device is accommodated on rollers 54, 54', thus permitting the entire shedding device to be extracted out of its guiding means (not shown) on the inner confronting sides of the said sidewalls 51.

The described apparatus operates as follows:

Before the beginning of the working (weaving) process the individual elements of the shedding device are in a position illustrated in FIG. 1, where there is shown an embodiment with a horizontal drive. The bell crank 32 of the control system 3 is held by the segment 42 of the device 4 for closing the shed waves, while its disc 321 is held in a position in which the axis of the eccentric pin 34 lies in the level of the axis V passing through the axes of the pins 221, 221' of the holder of the section 222. The heads 221 of the lever means 21 form, in the horizontal direction, a wave line corresponding with the angle of turning of each cam 12 of the drive 1. This horizontal wave line is transformed into a vertical wave line by the lifting means 2, determining the position of individual shaft rods, e.g. 25. Simultaneously, the shaft rods 27 are moved through the same distance from the axis of symmetry of said wave line, but in the opposite direction. The process goes on as follows:

The head 211 of the lever means 21 moves from the left to the right, and thus tips the three-arm lever 22 around the pin 221' of the holder 222 in a counterclockwise direction, i.e. the shaft rod 27 moves upwards, controlled by the guide lever 28, supported exactly over the three-arm lever 22. Through the effect of the connecting rod 23, its second arm transmits the movement to the double-arm lever 24 mounted on the common upper pin 221 of the holder of the section 222. Consequently, the shaft rod 25 connected with the double-arm lever 24 performs the movement downwards, turning the lower guide lever 26 counterclockwise around the lower pin 221' of the holder of the section 222, i.e. opposite the direction of rotation of the three-arm lever 22. After the loom has been switched on, the shaft 11 with the cams 12 starts rotating, and the links guided by glide members 13, 13' follow by means of the rollers 14, 14' the circumferences of the cams 12, rolling around the shouldered hubs 121 of cams 12. Thus the rotational movement is transformed into a linear one which is transmitted to the levers 21 which are swingable around the eccentric pins 34. Then the heads 211 of the lever means 21 impart a

wave-like harmoniously repeated movement by means of the lifting means 2, and a continuous shedding movement to the shaft rods 25, 27 in the direction of the picked weft threads (not shown).

- 5 In case a change of the adjustment of the height of shed waves is required, the bolts 302 of the control system 3 are loosened. By turning set screws 301 appropriately the entire system of bell cranks 32 is then moved as required, including the segments 42, on the brackets 10 30 in the vertical direction. During the upward movement, the slides 33 enter deeper into the forks 212 of the lever 21. The distance of the head 211 from the pin 210 of the lever 21 is constant, as is also the stroke of the link 15, but the distance between the pin 210 and the eccentric pin 34 has decreased, whereas the length of the path of the moving head 211 of the lever 21 has increased, thereby increasing the height of the shed wave. When the control system 3 starts its operation in the downward direction, the opposite situation sets in; 20 the path of the movement of the head 211 of the lever 21 has decreased and thus also the height of the shed wave is less.

The function of the device 4 for closing the shed waves comprises two operations dependent upon each other. Turning now to FIG. 9, first of all the fixed fulcrum of the lever 21 formed by the eccentric pin 34 of the slide 33 is eliminated by turning the shaft 41 with the arranged set of segments 42 by pulling the chain 44 by chain control means (not shown) in the direction X

- 25 from the position given by the axis Y₂ to the position of the axis X₂. At the beginning of this phase, the discs 321 are released from the grip of the open wedge of the segments 42. By the continuing pull of the chain 44, the spring 47 is tensioned and under simultaneous turning 30 of the sprockets 45, 46 the thus actuated movement is transmitted to the shafts 451, 461 of the profile bars 452, 462. Because the chain 44 is stretched between the sprockets 45, 46 crosswise, the profile bars 451, 461 turn in opposite directions from the position Y₁ to the position X₁.

As the result of both these rotary movements, the space between the profile bars 452, 462 becomes narrower, and the said bars start aligning the levers 21, which have formed a horizontal wave-line, into one row

- 45 by means of pressing upon the heads 211 of said levers. This is possible only because the forks 212 of the levers 21 have no fixed position and because the fulcrum point of the tipping levers 21 has been transferred to the axis of the pin 210 of the link 15. When the heads 211 have been aligned in a row through the action of the turned profile bars 452, 462 (see FIG. 9) a situation sets in wherein the axes of all members 221, 221', 211 will be in one common level V. The eliminated wave-line of the heads 211 will be again observed on the bell cranks 32 and their rollers 321. All arms of the levers 22, 26, as well as of the levers 24, 28 of the transmission device, have come into exact alignment and consequently also the eyes of the heddles (not shown) of the shafts have grouped themselves at the level of the weaving plane (not shown) of the loom.

By eliminating the force acting upon the chain 44 in the direction X, the tension of the spring 47 results in its movement in the direction Y. Through its effect, the profile bars 452, 462 turn from the position of the axes X₁ to the position of the axes Y₁, thus increasing the space between the profile bars 452, 462 to the original width. The chain 44, turning the sprocket 43 of the

shaft 41 tips the segments 42 from the position X_2 to the position Y_2 . Owing to the curvature 420 of the segments 42, the pressure in the upwards direction effects the discs 321 of the bell cranks 32 forming the lower half-waves of the shedding wave. The movement transmitted by the slide 33 on the fork 212 of the levers 21 adjusts the said fork at the level V. The levers 21 which have been tipped around the pin 210 actuates the stroke of one half of the shaft rods 25, 27 (the upper shed) by means of the respective levers of the lifting means 2. By continuing the tipping of the segments 42 in the direction towards the position of the axis Y_2 , the discs 321 of the bell cranks 32 forming the upper half-wave of the shedding wave-line bear consecutively against the function surface 421 of the segment 42. The pressure resulting from this contact, which is transmitted by the lever 21 on the transmission mechanism 2, brings about the movement of the remaining half of the shaft rods 25, 27 (the lower shed). The discs 321 are gripped by the wedge of the function parts 420, 421 of the segments 42; the position of the eccentric pins 34 is thus secured on level V and the loom is prepared for switching on.

Turning now to FIG. 2, there is there shown an embodiment of the present invention with a so-called vertical drive. Except for the control system 3 of FIG. 1, the embodiment of FIG. 2 is substantially identical therewith. The arrangement of lifting means 2 in FIG. 2 is the same as in FIG. 1, only the sidewalls 55 of FIG. 2 have been changed. A vertically movable link 151 has been also mounted on can 12 in the same way, while at the end with which it meshes with the horizontal arm of the three-arm lever 22 it is provided with an open groove 152 which is directed, in the central position of the stroke of the link 151, towards the turning point of said three-arm lever 22.

Every link is provided with a slot 153 with a transverse pin 416 which is connected, by means of at least two connecting bars 415, with the sleeves 414 of at least two eccentric members 411 arranged on a common shaft 410. The eccentric members 411 are further provided with fixed fingers 412, which are connected with one another by means of the rod 413. After the eccentric members 411 have been turned and the link 151 has been shifted out of engagement with the three-arm lever 22, rod 413 limits, at least from one side, the area of the dead centers of the lifting means 2, thus forming, in combination with the other driving means, the device 4 for closing the shed waves.

In the embodiment of FIG. 2, the vertical movement of the link 151 is derived from the cam 12 on the shaft 11 directly on the three-arm lever 22 of a transmission mechanism 2 as above-described. In order to closing the shed waves, the lifting means 2 must be disconnected from the drive mechanism 1. By turning the control shaft 410 counterclockwise, the eccentric member 411 rotates in the sleeve 412. The resultant horizontal force of their movement is transmitted by the connecting bars 415 on the transverse rod 416 in the grooves 153 of the links 151. The deflection of links 151 from the vertical position sets in, and the pins 155 of the three-arm levers 22 move out of engagement with the forks 152 of the links 151. With the rotating of eccentric members 411, the fingers 412, interconnected by the rod 413, lift from the position Z_1 . Approximately, during the second half of its stroke into the position Z_2 , the rod 413 begins to lift one half of the

three-arm levers 22 one after the other and one half of the guide levers 26 forming the wave-line of the shaft rods 25, 27 of the lower shed. As long as there are three-arm levers 22 in the section of the transmission mechanism 2 in the lower half of the working stroke, they are lifted by the pressure of the rod 413, until the guide levers 26 bear against the rod 413 in a counter-motion derived from the said three-arm levers 22 by means of double-arm levers 24 and shaft rods 25. If there are guide levers 26 in the lower half of their stroke at the given moment, the force imposed upon them by the rising lever 413 causes all shaft rods 25, which have been forming the lower shed to move upwards, as well as the arms of the double-arm levers 24 connected with the bars 25, to rise. The other arms of these levers, moving in the opposite direction, press the three-arm levers 22 with the connected shaft rods 27 by means of the connecting rods 23 until the shed waves are closed at the moment determined by the position Z_2 of finger 412 of the eccentric member 411. In this position the whole transmission mechanism 2 can be shifted in the sidewalls 55 in the direction of the warp beam. This is also the only suitable position for disassembling the machine. The preparation of the shedding mechanism for the working position, i.e. the simultaneous opening of the shed waves, is performed by turning the shaft 410 with the eccentric members 411 from the position Z_2 to the position Z_1 . The rod 413, supported by the fingers 412 of the eccentric members 411, releases the support of the three-arm levers 22 and the lower guiding levers 26. Simultaneously, the connecting rods 415 attract the links 151 from the tipped position into the vertical position by means of the transversal rod 416. The pins 155 on the three-arm levers 22, which have been arranged into a vertical wave-line, are drawn to the narrowed part of the fork 152 by means of the movement of the links 151 and through the cooperation of the broadened forks 152 of the links 151. During the said drawing-in of the pins 155 the shaft rods 25 and 27 assume positions corresponding with the position of the cams 12 of the shaft 11 of the drive mechanism 1. The entire transmission system is then able to reproduce the movement determined by the drive mechanism 1.

Although the invention has been illustrated and described with reference to a plurality of preferred embodiments, it is to be expressly understood that it is in no way limited to the disclosure of such a plurality of embodiments, but is capable of numerous modifications within the scope of the appended claims.

What is claimed is:

1. In a wave weaving loom, an apparatus for controlling the movement of shaft rods, the apparatus being arranged in a frame and divided into sections extending across the loom, each section comprising
  - an upper one-armed guiding lever swingably mounted on an upper pin in the frame,
  - an upper double-arm lever swingably mounted on the upper pin,
  - a lower one-armed guiding lever swingably mounted on a lower pin,
  - a lower three-arm lever swingably mounted on the lower pin,
  - a front shaft rod jointly connected to one arm of the upper double-arm lever and to the lower one-armed guiding lever,

a rear shaft rod jointly connected to one arm of the lower three-arm lever and to the upper one-armed guiding lever,
 a connecting rod jointly connecting the second arm of the upper double-arm lever with the second arm of the lower three-arm lever, 5
 a double-arm driving lever, one arm of which being jointly connected by means of a head to the third arm of the three-arm lever,
 a driving mechanism jointly connected to the double-arm driving lever, 10
 a swingable bell crank, one arm of which being swingably and shiftably connected to the second arm of the double-arm driving lever,
 a segment disposed on a shaft extending across the loom and securing the second arm of the bell crank, 15
 two rotatable profile bars arranged on both sides of the head and extending across the loom, the rotatable profile bars being coupled to the segment.
 2. Apparatus according to claim 1, comprising a sprocket attached to the shaft, 20
 two sprockets, one of which is attached to one of the rotatable profile bars, the second being attached to the other rotatable profile bar,
 a chain tensioned by a spring and meshing with the sprocket of the swingable segment via the two sprockets of the profile bars.
 3. Apparatus according to claim 1, comprising a fork on the second arm of the double-arm driving lever, 30
 a slide slidably mounted in the form and jointly connected to one arm of the bell crank,
 a bracket extending across the loom and slidably mounted in the frame and in which the shaft is rotatably mounted and the bell crank swingably mounted, 35
 a set screw for shifting the bracket and arranged in the frame, and
 a bolt for securing the bracket in its position.
 4. Apparatus according to claim 1 comprising a drive shaft extending across all the sections of the apparatus,

a cam disposed on the drive shaft and displaced with respect to cams of other sections with a certain phase shift, said cam being provided with a shouldered hub on both of its sides,
 a double bifurcated link jointly connected to the double-arm driving lever,
 two parallel glide members arranged on the double bifurcated link and being in contact with the shouldered hub,
 two rollers engaging the cam on either side thereof, two cross bars on which a roller is rotatably mounted and adjustably mounted on the link, each of the cross bars being provided with a slot through which a fixing bolt extends.
 5. Apparatus according to claim 1, wherein the frame comprises two sidewall members connected to each other by cross beams and equipped with rollers and separably mounted in the loom.
 6. Apparatus according to claim 5, wherein the upper pin and the lower pin are mounted on a holder, the latter being removably mounted in the frame and wherein the head is disengageable.
 7. Apparatus according to claim 1, wherein the axes of the pins and the rotating axis of the bell crank lie on a common straight line.
 8. Apparatus according to claim 1, comprising a vertically movable link coupled to the driving mechanism, said link engaging the third arm of the three-arm lever and being provided with a slot, a transverse pin extending through the slots of the links of all the sections, at least two horizontal connecting bars arranged on both sides of the apparatus, sleeves fixed to the ends of the connecting bars, eccentric members arranged on a common shaft and rotatably mounted in the sleeves, fingers fixed on the eccentric members, and a rod connecting the fingers.
 9. Apparatus according to claim 8, comprising a pin on the third arm of the three-arm lever, said last-named pin engaging a groove in the link.
